TOY BANK

James E. Thomson, Munith, Mich., assignor to Western
Stamping Company, Jackson, Mich., a corporation of
Michigan

Filed Nov. 14, 1961, Ser. No. 67,512

Term of patent 14 years

(Cl. D34—11)

FIGURE 1 is a front elevational view of a toy bank in accordance with my new design;

FIGURE 2 is a side elevational view of the toy bank of FIGURE 1; and

FIGURE 3 is a perspective view of the toy bank with the door thereof in the partially open condition.

The back and the side of the toy bank opposite to that of FIGURE 2 comprise flat panels substantially devoid of ornamentation.

The characteristic feature of my design for a toy bank resides in a circular door having a transparent frontal face to expose a gear complex comprising a centrally disposed sun gear and a plurality of circumferentially spaced planetary gears with radially outwardly extending members between the planetary gears.

I claim:

The ornamental design for a toy bank, as shown and described.
